UNITED STATES PATENT OFFICE.

GARRY P. VAN WYE, OF NEW YORK, N. Y.

SOAP-DISPENSER.

1,048,919.

Specification of Letters Patent. Patented Dec. 31, 1912.

Application filed April 27, 1909. Serial No. 492,540.

To all whom it may concern:

Be it known that I, GARRY P. VAN WYE, a citizen of the United States, residing at New York, in the county and State of New 5 York, have invented a new and useful Soap- Dispenser, of which the following is a specification.

This invention relates to devices for holding and dispensing soap; and the object thereof is to provide a device of this kind which will receive any cake of soap usually made for toilet purposes, and will dispense the same as desired; a further object being to provide a device of this character that 15 will be strictly sanitary; that will hold the soap in public places without danger of being carried off; and that can be used any number of times while washing without splashing the same with water, or having 20 the water run into the holder.

The invention is illustrated in the accompanying drawing in which—

Figure 1, is a face view of a soap dispenser constructed according to my invention; Fig. 2, is a vertical section thereof, on the line 2—2 of Fig. 1; Fig. 3, is a top plan view thereof; Fig. 4, is a horizontal section on the line 4—4 of Fig. 2; and, Fig. 5, is a view on a larger scale of one of the teeth.

In the drawing, like numerals of reference refer to the same parts in each of the views, and in practice I provide a soap dispenser comprising a casing 6, having a hinged lid 7, which is hinged at 8, to a cylinder 9, having wings, or flanges 10, to which the casing 6, may be secured by rivets 11, or in any desired manner, while a pipe 12, will serve in conjunction with the cylinder 9 to secure the dispenser to a wall, or to any support, 40 as will be understood. I may also provide a lock 13, to prevent the removal of the soap.

The casing 6, is provided with a soap receptacle 14, and with a rectangular part 15, extending from the top of the casing and 45 projecting below the bottom of the holder 14, as shown at 16. The part 15, is greater in width than the receptacle 14, whereby shoulders 17, are formed, as clearly shown in Fig. 4.

Mounted in the rectangular part 15, is a cutting, or shaving device comprising a plate 18, having a plurality of teeth 19, preferably of the shape shown in Fig. 5, so that the teeth will cut on the downward stroke 55 only. The plate 18, is greater in width than the soap receptacle 14, so that at the sides

the plate will engage the shoulders 17, and the plate is provided with lateral flanges 20, of a size to fit the edges of the rectangular part 15, thus making a slidably mounted 60 shaving device within the rectangular part 15, and forming a wall for the receptacle 14, with the teeth projecting therein and pointed downward, as shown. The shaving device is provided at the top thereof with a flange 21, provided centrally thereof with a depression 22, more particularly shown in Fig. 1. In this depression I mount a roller 23, and a link 24, passing through a slot 25, in this flange, and provided with a hole 70 therethrough in which said roller is mounted, serves as a connecting means between the shaving device and the operating lever 26. This operating lever is pivotally connected with the casing at 27; and at the free end 75 thereof, without the casing, the lever is provided with a downwardly-inclined part 28, ending with a thumb-piece 29, which may be formed integral with the lever.

The link 24, is pivotally connected with 80 the lever 26, at 30, and is provided with a shoulder 31, adapted to bear against the depressed part 22, of the flange 21, so the link can not be pulled up through the slot 25, in said flange; and this link is provided with 85 an extension 32, to which is connected a spring 33, which preferably passes up within the cylinder 9, to a pin 34, passing through the upper part thereof, in order to give the spring sufficient room for proper 90 working without making the casing longer than necessary to provide for the other parts. I may also use pins 35, through the roller 23, to retain the same in the link 24.

To insure the feeding of the soap to the 95 shaving device, the bottom of the soap receptacle is sharply inclined, as shown at 36, in Fig. 2, on which a cake of soap, as 37, is adapted to rest.

In operation, the spring 33, holds the shay- 100 ing device in a raised position, as shown in full lines in Fig. 2, at which time the lower end of the shaving plate is below the soap receptacle; and this lower end is free of teeth for a distance equal to the length of 105 the stroke. A cake of soap having been placed in the receptacle, and resting on the inclined part 36, thereof, is fed by its own weight to the teeth 19, of the plate 18, and when this plate is forced down by the lever 110 26, against the action of the spring 33, the teeth 19, will shave off a small portion of the

soap, which will drop through the open bottom 38, of the rectangular part 15, and may be caught in the hand, as will be understood. On releasing the pressure on the 5 thumb-piece 29, the spring 33, will cause the shaving plate to rise; and if more soap is desired, another stroke may be made, and the operation continued until sufficient soap has been obtained, as will be understood. 10 As the edge of the cake of soap against the shaving plate is shaved off, the cake will descend the inclined part 36, until the entire cake is consumed. To insure that none of the cake shall pass through in lumps, I have 15 provided a pocket 39, at the bottom of the incline, into which the bottom teeth may enter at the down stroke, as indicated in dotted lines in Fig. 2, the position of the lower end of the shaving plate and flanges being also indicated in dotted lines. This 20 pocket is large enough to receive the bottom row of teeth, but not large enough to allow the remaining portion of a cake of soap to enter until so nearly consumed that the lower teeth will readily pulverize it. Thus 25 the entire cake is consumed without any waste whatever. It will also be understood that a second cake may be placed on top of the first cake before the first cake is consumed, and the shaving device will not only 30 continue to act on the first cake, possibly even more effectively owing to the weight of the second cake on the first one; but may also act on the second cake should any part thereof come in contact with the shaving device. 35 Or the receptacle may be filled with cakes without interfering with the effectiveness of the dispenser, care being taken to have the spring 33 strong enough to insure the return of the shaving device after each 40 stroke.

It will be observed that I have made the thumb-piece 29, practically on a level with the bottom of the main portion of the lever 45 26, so that water will never drain into the receptacle from the thumb-piece. Further, as the lever 26, is provided with the inclined part 28, the drainage will always be away from the receptacle should any water be 50 thrown or dropped on the lever; and the contents of the receptacle will be kept perfectly dry.

To prevent the shaving device rising above the position shown in Figs. 1 and 2, I 55 have provided a stop 40, in the channel of the rectangular part 15, so that the shaving device can never be raised high enough to carry the lower end above the bottom of the soap receptacle. Likewise, on account of 60 this stop, the lever 26, can not rise above a horizontal position, and, consequently, there can be no drainage from the wet hand of the operator into the soap receptacle.

It will thus be seen that I have provided 65 a simple and efficient soap dispenser, and

one that is perfectly sanitary for the reason that no one can touch the cake of soap. Further the cake of soap is kept perfectly dry until entirely consumed; and the person using it will always have the advantage of 70 using perfectly fresh soap. Then, too, the device is so constructed that any kind of toilet soap can be used with it, whether the cheapest, or most expensive variety; and as no one can touch the cake of soap, it can be 75 used in public places in a perfectly sanitary manner, all that is necessary being to keep the thumb-piece 29, clean.

Having thus described my invention, what I claim as new and desire to secure by Letters Patent of the United States is—

1. A soap dispenser comprising a casing, a shaving device slidably mounted therein and forming substantially one side of the soap receptacle in said casing, the base of 85 said soap receptacle being inclined toward said shaving device, and said base having a pocket therein adjacent to said shaving device, for the purpose set forth.

2. A soap dispenser comprising a casing, 90 a shaving device mounted therein, a lever passing through said casing adapted to operate said shaving device, said lever having a portion without the casing adapted to be engaged by the hand of an operator, 95 means to limit the movement of said lever to a substantially vertical plane, and means to prevent the hand-engageable portion of said lever rising above the horizontal plane 100 of any part of said lever.

3. A soap dispenser comprising a casing, a shaving device mounted therein, a lever passing through said casing adapted to operate said shaving device and means to prevent the lever rising above a horizontal 105 position, the part of said lever outside of said casing being downwardly inclined, for the purpose set forth.

4. A soap dispenser comprising a soap receptacle, a vertically movable shaving device forming one side of said receptacle, a lever adapted to operate said shaving device, said lever having a thumb-piece below the body portion thereof, and means to prevent the lever rising above a horizontal position for the purpose set forth.

5. A soap dispenser comprising a casing, a vertically movable shaving device mounted therein, a lever mounted in said casing and adapted to operate said shaving device, said lever extending horizontally through said casing and means to limit the operation of said lever from the horizontal position downward, and said lever having a downward inclined portion without the casing 125 ending with a thumb-piece below the portion of the lever within the casing.

6. In a soap dispenser, a shaving device having a plurality of teeth downwardly directed with flat cutting edges, said dispenser 130

having a soap receptacle with a base inclined downward facing said teeth, and means to reciprocate said shaving device.

7. In a soap dispenser, a shaving device comprising a plate provided with teeth and having an angled top with a depression therein, a pivoted lever, a link connecting said lever and said shaving device, said link passing through a slot in said angled part, a 10 roller in said depression passing through said link, said link having a step or shoulder engaging the under side of said depression, and a spring controlling said shaving device, as and for the purpose set forth.
- 15 8. In a soap dispenser, a casing having a soap receptacle, a vertically movable shaving device therein forming one side of the soap receptacle, a lever to operate said shav-

ing device, a cylinder forming part of the support, secured to the top of said casing, 20 and a spring engaging said shaving device and extending within said cylinder, as and for the purpose set forth.

9. A soap dispenser comprising a casing, a shaving device mounted therein, a lever 25 passing through said casing adapted to operate said shaving device, and means to limit the movement of said lever in a substantially vertical plane and means to prevent said lever rising above a horizontal position. 30

Dated this 26th day of April, 1909.
